UNITED STATES PATENT OFFICE.

CHAS. KINZLER AND WM. ROSEBROCK, OF NEW YORK, N. Y.

IMPROVED APPARATUS FOR CUTTING OR DIVIDING LOAF-SUGAR.

Specification forming part of Letters Patent No. **28,183**, dated May 8, 1860.

To all whom it may concern:

Be it known that we, CHARLES KINZLER and WILHELM ROSEBROCK, both of New York, in the county and State of New York, have invented a new and Improved Machine for Cutting Loaf-Sugar in Slabs; and we do hereby declare that the following is a full and exact description thereof, reference being had to the accompanying drawings, and to the letters of reference marked thereon.

Figure I represents a cross-section, and Fig. II a front view, of the machine. Fig. III shows a top view, with the circular saws removed.

The nature of our invention consists in the arrangement of a revolving finger-frame, which takes the loaf of sugar from a fixed table, carries the same through a number of circular saws, which cut the loaf in slabs, and then deposits the slabs on a table at the back of the machine. On a shaft, A, a number of circular saws, S S, &c., are firmly secured, of such a size as to cut through the largest part of a loaf of sugar, and at a distance from each other equal to the thickness the slabs are to be cut. Below those circular saws the finger-frame B is situated, turning in bearings in the upright frame F. To this frame B shafts N M are fitted, capable of turning, and which said shafts are provided with a number of arms or levers, n and m, acting together similar to pinchers, and so arranged on the shafts N and M as to pass between the circular saws S S while revolving. The inner sides or edges of the arms n and m are so arranged and shaped in such a manner as to correspond with the external tapering shape of a loaf of sugar. The other ends, m', of the levers m are connected together by a bolt, D, the ends of which work in an eccentric groove, E, for the purpose hereinafter mentioned. This bolt D is connected by levers and rods (shown in the drawings in blue lines) with the arms n in such a manner as to operate those arms n simultaneously with the arms m. The eccentric groove E, in which the ends of the bolt D works, is so constructed as to keep the arms n and m closed while the same are passing between the saws S S, so as to hold the loaf of sugar during that time perfectly tight, and then to open said arms n and m, to allow the slabs into which the loaf of sugar has been cut up while passing through the

saws to fall out, and remain open until another loaf of sugar has been taken hold of. This eccentric groove E is fixed on a lever, G, turning on a center, g, in the frame F, the extreme end of which lever G is acted upon by a weight, W, or spring, so regulated as to keep the eccentric groove E in a certain position, and in which position the arms n and m will be closed or opened sufficiently to admit and hold a certain size loaf-sugar. Whenever a loaf of sugar is introduced between the arms which is either larger or smaller, the arms n and m must close either less or more, to hold the same tight between them, in which case the weight on the extreme end of the lever G is counteracted, and allows that end which carries the eccentric groove E to move so much as to give the required motion to the arms n and m, to hold the different sizes of loaf firmly between them. Before the machine is a table, T, fixed upon which the loaves of sugar are placed. That side of this table next the machine is provided with long projections or fingers w, so that the arms n and m can pass between said projections and take hold of the loaf of sugar lying on the same. The arms n m are then closed around the loaf, so as to hold the same firmly between them, as above described, and carry said loaf of sugar through the revolving circular saws to be cut into slabs, after which the arms are again opened, so as to allow the slabs to fall upon the table V, at the back of the machine, which said table is likewise provided with projections or fingers x, between which the arms n and m can pass while revolving, and by which arrangement the tables T and V can be brought up close to the revolving finger-frame B. The table T is inclined toward the machine, so as to bring the loaf of sugar near the machine, ready for the arms m to take hold of, and the table V is inclined from the machine to allow the slabs of sugar to slide away from the arms m n and clear of the machine. In the accompanying drawings only two sets of arms, n and m, are shown; but three or four sets may be used. The circular-saw shaft A is provided with a pulley, X, through which motion is communicated to the same, and the other end of said shaft is provided with a pinion, 2, acting into gearing, and communicates thereby the required motion to the

drum H on the shaft J of the finger-frame B. The drum H runs loose on the shaft J, and is connected with the sliding clutch K, working either on a square part or on a feather on the shaft J, and communicates through the same the required motion to the shaft J, and consequently to the finger-frame B. The clutch K is attached to the end of a lever, L, turning on a fulcrum, 3, the other end of which lever is acted upon by a spring, U, or by a weight, and so regulated that any increase of resistance will cause the drum H to slide or slip on the clutch K, diminishing thereby the speed of the finger-frame B, or stop the same altogether, until the excess of resistance has been overcome. By this arrangement the resistance offered to the circular saws at the beginning, or when the same begin to act upon the loaf, will be equal to the resistance offered when the saws are cutting through the center of the loaf.

Instead of connecting the circular-saw shaft with the finger-frame shaft through gearing, a belt may be placed on the drum H and driven direct.

What we claim as our invention, and desire to secure by Letters Patent, is—

1. The combination and arrangement, with circular saws, of the revolving frame B, provided with arms n and m, operating in such a manner as to take hold of a loaf of sugar, carry the same through the saws, and deposit the cut slabs upon a suitable table, substantially as specified.

2. The arrangement of attaching the eccentric groove E to a movable lever operating in the manner described, and for the purpose set forth.

3. The manner of working the revolving finger-frame B by means of the clutch K, acted upon by the lever L, in the manner and for the purpose substantially as described and specified.

CHARLES KINZLER.

WILHELM ROSEBROCK.
